UNITED STATES PATENT OFFICE.

EDWARD V. BOILER, OF WEST SIDE, IOWA.

AEROPLANE.

1,353,212.

Specification of Letters Patent. Patented Sept. 21, 1920.

Application filed January 29, 1920. Serial No. 354,919.

To all whom it may concern:

Be it known that I, EDWARD V. BOILER, a citizen of the United States, residing at West Side, in the county of Crawford and State of Iowa, have invented certain new and useful Improvements in Aeroplanes, of which the following is a specification.

My invention relates to improvements in aeroplanes.

10 An important object of the invention is to provide an aeroplane which operates upon the principle of an inclined plane to raise the machine into the air, when propelled forwardly, at high or low speeds.

15 A further object of the invention is to so construct the aeroplane that it may be easily controlled in flight, little affected by air currents, and at all times maintaining a state of balance in flight, thereby preventing

20 side slipping.

A further object of the invention is to provide longitudinal stabilizing wings, of large area, which not only effectually prevent slide slipping, but compensate for the 25 loss in wing-spread, due to the reduction in size of the sustaining wings or planes.

A further object of the invention is to provide means to adjust the dihedral angle of the longitudinal stabilizing wings.

30 A further object of the invention is to provide a flying machine of the above-mentioned character, having its sustaining and stabilizing wings so connected with and arranged with relation to the fuselage, that the 35 machine as a whole has a low center of gravity, and the planes are disposed in the whip stream of the propeller, whereby they are subjected to substantially the same air conditions, at all times, during flight.

40 A further object of the invention is to provide longitudinal stabilizing wings which are cambered, and adapted to function as true sustaining planes, in addition to their stabilizing action.

45 Other objects and advantages of the invention will be apparent during the course of the following description.

In the accompanying drawings forming a part of this specification, and in which like numerals are employed to designate like parts throughout the same—

Figure 1 is a plan view of an aeroplane embodying my invention.

Fig. 2 is a side elevation of the same,

55 Fig. 3 is a front end elevation of the same,

Fig. 4 is a transverse section through the fuselage, taken on line 4—4 of Fig. 2, parts being omitted,

55 Fig. 5 is a similar view taken on line 5—5 of Fig. 2,

Fig. 6 is a similar view taken on line 6—6 of Fig. 2, and,

Fig. 7 is a perspective view of an operating lever and associated elements.

In the drawings, wherein for the purpose 65 of illustration is shown a preferred embodiment of my invention, the numeral 5 designates the fuselage of the aeroplane, having the cockpit 6, arranged as shown. The motor 7 is carried in the forward end of the 70 fuselage, and drives the tractor propeller 8, as shown. The fuselage has its forward portion supported upon a chassis 9, and a skid 10 is secured to its rear portion.

The numeral 11 designates the transverse 75 supporting planes, arranged upon opposite sides of the fuselage and rigidly secured thereto. I preferably employ diagonal struts 12, connected with the supporting planes 11, near their outer ends, and with 80 the fuselage 5, near its bottom, as shown.

The rear edges of the supporting planes 11, which are cambered, are cut away, providing spaces 13, receiving ailerons 14, hinged thereto, at 15, by any suitable means. 85 The usual masts 16 are rigidly secured to the supporting planes 11, and carry elements 17, engaging cables 18, which extend to the cockpit 6, and are operated by the usual joy stick.

The numeral 19 designates the longitudinal stabilizing planes, which are cambered and tapered longitudinally, increasing in width rearwardly. These stabilizing planes are suitably hinged, as at 20, to the 95 fuselage 5, and are normally arranged at a slight dihedral angle. Both the supporting planes and the stabilizing planes 19 are disposed at the upper longitudinal edges of the fuselage. The stabilizing planes are 100 therefore normally inclined with the fuselage, as shown in Fig. 2.

Means are provided to swing the stabilizing planes 19 upon their pivots 20, to vary the dihedral angle thereof, comprising diagonal struts 21, secured to the outer edges of the stabilizing planes, preferably having pivotal connection therewith. The struts 21 are provided at their lower ends with sockets 22, receiving balls 23, carried by 110

vertically adjustable shafts 24. The shafts 24 operate within sleeves 25, angularly disposed, and rigidly secured to the fuselage 5. The shafts 24 extend to the exterior of 5 the fuselage, as clearly shown in Fig. 4.

Extending longitudinally within the fuselage 5 are rock shafts 26 and 27, journaled in bearings 28, rigidly secured to the fuselage. These rock shafts carry sprocket 10 wheels 29, rigidly secured thereto, and connected by a sprocket chain 30, so that the two rock shafts turn in unison in the same direction.

Each rock shaft 26 and 27 is provided 15 with a plurality of cranks 31, 32 and 33, rigidly secured thereto, and having pivotal connection with links 34, pivoted to the shafts 24. These cranks are of different lengths, increasing in length rearwardly, so 20 that they will move all portions of the stabilizing plane 19 a corresponding distance.

One rock shaft 27 is shown as equipped 25 with a worm 35, engaged by a worm 36, rigidly secured upon a transverse shaft 37, arranged within the fuselage. This shaft is 30 turned by a lever 38, positioned to be operated by the party in the cockpit 6.

From the foregoing description, it will be 35 seen that the stabilizing planes 19 are normally locked in a suitable dihedral angular position, which may be varied by the operation of the lever 30. The ailerons 14, the elevators 32, and vertical rudder, are operated in the usual manner, as is well known in 40 the art, whereby it is thought to be unnecessary to further describe the same, it being understood that any suitable means may be employed for that purpose. By arranging the stabilizing planes and supporting planes 45 at or near the upper edge of the fuselage, and imparting to them a dihedral angle, the machine has a very low center of gravity, and further practically all parts of the machine are arranged in the whip stream of 50 the propeller, so that the machine is not subjected to the change in air conditions, to any considerable extent, during flight.

It is to be understood that the form of my 55 invention herewith shown and described is to be taken as a preferred example of the same, and that various changes in the shape, size, and arrangement of parts may be resorted to without departing from the spirit of my invention, or the scope of the subjoined claims.

Having thus described my invention, I claim:—

1. An aeroplane comprising a fuselage, supporting planes connected therewith and 60 arranged upon opposite sides thereof, longitudinal stabilizing planes arranged upon opposite sides of the fuselage in the rear of the supporting planes, and pivotally connected with the fuselage near its top, said 65 stabilizing planes tapering longitudinally

and increasing in width rearwardly, a plurality of spaced elements secured to the stabilizing planes near their outer edges and extending inwardly toward the fuselage, means to simultaneously move the elements 70 upon each side of the fuselage and to move each succeeding rear element a greater distance than the next preceding forward element and propelling means carried by the fuselage.

2. An aeroplane of the character described, comprising a fuselage, supporting planes connected with the fuselage and arranged upon opposite sides thereof, longitudinal stabilizing planes arranged upon 80 opposite sides of the fuselage and pivotally connected therewith, said stabilizing planes extending from a point adjacent the supporting planes to a point adjacent the rear end of the fuselage, said stabilizing planes 85 tapering and increasing in width rearwardly, a plurality of spaced elements arranged upon each side of the fuselage and connected with the stabilizing plane near its outer edge, said elements being inclined 90 inwardly toward the fuselage, means carried by the fuselage to simultaneously move all of said elements and to move the elements in each set for different distances, and propelling means carried by the forward 95 end of the fuselage.

3. An aeroplane of the character described, comprising a fuselage, supporting planes connected therewith and arranged upon opposite sides thereof, longitudinal 100 stabilizing planes arranged upon opposite sides of the fuselage in the rear of the supporting planes and pivotally connected with the fuselage, said stabilizing planes tapering longitudinally and increasing in width 105 rearwardly, a plurality of diagonal struts connected with each stabilizing plane and inclined downwardly toward the fuselage, a corresponding number of pivoted elements carried by the fuselage and connected with 110 the struts, said pivoted elements increasing in diameter rearwardly, and propelling means carried by the fuselage.

4. An aeroplane comprising a fuselage, supporting planes connected therewith and 115 arranged upon opposite sides thereof, longitudinal stabilizing planes arranged upon opposite sides of the fuselage in the rear of the supporting planes and connected with the fuselage near its top, said stabilizing 120 planes tapering longitudinally and increasing in width rearwardly, diagonal struts connected with the outer edges of the stabilizing planes and converging downwardly toward the bottom of the fuselage, means 125 to longitudinally move the struts with relation to the fuselage, and propelling means connected with the forward end of the fuselage.

5. An aeroplane comprising a fuselage 130

which is longitudinally tapered and decreases in width rearwardly, supporting planes arranged upon the opposite sides of the forward portion of the fuselage and connected therewith, the fuselage extending forwardly beyond said planes, longitudinally tapered stabilizing planes increasing in width rearwardly and pivotally connected with the tapered side of the fuselage in 5 the rear of the supporting planes, diagonal struts pivotally connected with the tapered stabilizing planes near their longitudinal

edges and converging downwardly toward the fuselage, means arranged upon the fuselage to longitudinally adjust said struts, a 15 propeller connected to the forward end of the fuselage, and means to drive the propeller.

In testimony whereof I affix my signature in presence of two witnesses.

EDWARD V. BOILER.
